GARMENT HANGER

Leonard A. Young, Detroit, Mich.

Application April 7, 1933, Serial No. 664,867

10 Claims. (Cl. 223—62)

The main objects of this invention are:

First, to provide a garment hanger in which the body or garment supporting arm portions are of considerable diameter, thereby presenting a 5 suitable garment supporting surface and at the same time providing a structure which is very light and still has the desired strength and rigidity.

Second, to provide a garment hanger presenting 10 non-metallic surfaces to coat or body garments which are likely to be dampened, as by perspiration, when placed upon the hanger.

Third, to provide a garment hanger which is 15 very economical to produce and is at the same time strong and rigid.

Objects pertaining to details and economies of my invention will definitely appear from the description to follow. The invention is defined in the claims.

20 A structure embodying the features of my invention is clearly illustrated in the accompanying drawing, in which:

Fig. 1 is a side elevation of a garment hanger made in accordance with one embodiment of my 25 invention.

Fig. 2 is an enlarged detail section showing structural features thereof.

Fig. 3 is a transverse section through the cross member or bar on line 3—3 of Fig. 1.

30 Fig. 4 is a similar cross section of a modified form of cross member or bar.

Fig. 5 is a fragmentary side elevation illustrating another embodiment of my invention in which the cross bar is formed of wire.

35 Fig. 6 is a fragmentary elevation of still another embodiment of my invention in which the cross bar is formed of wire to constitute a garment clamping member.

The body or arm portion of my garment hanger, designated generally by the numeral 1, is 40 formed of a paper tube made up of spirally twisted strips of paper as indicated, these strips of paper being secured together by suitable adhesive. This paper tube is bent into angular form to provide 45 a pair of downwardly diverging arms 2. In the manufacture of the tubes they are preferably cut into proper length and bent to the angular position prior to drying of the glue or adhesive, and when dried retain this position to facilitate future operations in forming the hanger.

50 The cross piece 3 is formed of light weight metal, preferably of curved channel cross section disposed facing downwardly and terminating in flattened ends 4 which are turned upwardly and inwardly to provide hooks 5 which are disposed

within the ends of the arms 2 and clamped on the lower wall portions 6 thereof. This cross bar forms a garment supporting member of substantial width and it also stiffens and reinforces the arms 2, preventing their becoming distorted 60 or their lower ends spreading or collapsing under the weight of the garment or in handling the hanger.

The suspending hook 7 is provided with a shank 8 terminating in an eye 9 engaged with the angle or apex of the arms and the end of the eye being wrapped around the shank as shown at 10. With this arrangement of parts I secure a non-metallic garment supporting surface. Paper is 70 highly regarded for this purpose, metal hangers having been covered with fabric or paper to overcome the objections to metal. The body or arm portion of the hanger may be formed of comparatively light weight tubing and still is very strong and rigid, particularly when supported by 75 the metal cross bar as I have illustrated. The metal cross bar is not generally regarded as objectionable. The paper tubing is also of such diameter as to present a supporting surface of substantial area. As shown in Fig. 4, the cross 80 piece is longitudinally fluted or corrugated, instead of being channeled as shown by Fig. 3. This provides a rigid cross piece which resists bending to a marked degree.

In the modification or embodiment shown in 85 Fig. 5 the cross piece 11 is formed of wire and this has inturned ends 12 corresponding to the in-turned ends 5 of the cross piece 3. These in-turned ends are disposed within and clamped upon the arms 2.

90 In the embodiment shown in Fig. 6 the arms 2 are braced and supported by a cross member which also constitutes a garment clamp. This is formed of a single piece of wire bent upon itself to provide a fixed cross piece 13 and a clamping member 14. The right end of the loop of wire is formed into a coil 15, or is coiled around one of the arms 2. The other end of the arm 13 is formed in a coil 16 or is coiled around the other arm 2 and terminates in an upwardly facing catch or keeper 17 with which the end of the arm 14 is detachably engaged so that it may be released to receive a garment and re-engaged to clamp the garment between the members 13 and 14. This form of cross bar also effectively supports and 95 braces the arms or body of the hanger and provides the additional feature of a trousers clamp. The structure has the disadvantage, however, of there being a small portion of metal to which the body garment arranged thereon is exposed.

110

In the embodiment shown in Figs. 1-5, inclusive, the ends of the arms are preferably cut square so that the upper portions thereof overhang and project beyond the ends of the cross bar 5 engaged therewith.

My improved hanger is economical in its parts and very easily assembled. I have not attempted to illustrate other forms or embodiments of my invention as it is believed that this disclosure will 10 enable those skilled in the art to embody or adapt my improvements as may be desired.

Having thus described my invention, what I claim as new and desire to secure by Letters Patent is:

- 15 1. In a garment hanger, the combination of downwardly diverging arms formed integrally of a hollow paper tube, a downwardly facing U shaped cross piece having upturned flattened ends disposed within the ends of said arms and clamped 20 upon the lower portion or wall thereof whereby said cross piece constitutes a reinforcing member and prevents the spreading of the lower ends of the arms, and a suspending hook having a shank wrapped around the apex of the arms to reinforce 25 the side walls of the tube.
2. In a garment hanger, the combination of downwardly diverging arms formed integrally of a hollow paper tube, a cross piece having upturned ends disposed within the ends of said arms and 30 clamped upon the lower portion or wall thereof whereby said cross piece constitutes a reinforcing member and prevents the spreading of the lower ends of the arms, and a suspending hook having a shank wrapped around the apex of the arms to 35 reinforce the tube against collapse.
3. In a garment hanger, the combination of downwardly diverging arms formed integrally of a single hollow paper tube, and a downwardly facing U shaped cross piece having upturned flattened ends disposed within the ends of said arms and clamped upon the lower portion of the wall thereof whereby said cross piece constitutes a reinforcing member and prevents the spreading of the lower ends of the arms.
- 45 4. In a garment hanger, the combination of downwardly diverging arms formed integrally of a single hollow paper tube, and a cross piece having upturned ends disposed within the ends of

said arms and clamped upon the lower portion of the wall thereof whereby said cross piece constitutes a reinforcing member and prevents the spreading of the lower ends of the arms.

5. In a garment hanger, the combination of a 80 hollow paper tube formed of spirally wound strips of paper bent to an angular form providing downwardly diverging arms, a metal cross piece having infolded ends disposed within and in clamping engagement with the ends of the tube, and a suspending hook having an eye embracing the tube at the angle thereof to reinforce the side walls of the tube.

6. In a garment hanger, the combination of a 90 hollow paper tube bent to an angular form providing downwardly diverging arms, a cross piece having infolded ends in clamping engagement with the ends of the tube, and a suspending hook having an eye embracing the tube at the angle thereof to reinforce the side walls of the tube.

7. A garment hanger comprising downwardly diverging arms formed of a bent hollow paper tube, a cross piece of curved cross section having its ends disposed within and clamped upon the ends of said arms, and a suspending hook of wire 100 having a shank terminating in an eye embracing the tube at the angle thereof to reinforce the side walls of the tube.

8. A garment hanger comprising downwardly diverging arms formed of a bent hollow paper 105 tube, a cross piece having its ends clamped upon the ends of said arms, and a suspending hook having a shank embracing the tube at the angle thereof to reinforce the side walls of the tube.

9. A garment hanger comprising downwardly 110 diverging arms formed integrally of a hollow paper tube, a suspended hook having a shank embracing said tube at the apex thereof to reinforce the side walls of the tube, and a cross piece having infolded ends disposed within and clamped 115 upon the ends of the tube.

10. A garment hanger comprising downwardly diverging arms formed integrally of a hollow paper tube, a suspended hook having a shank embracing said tube at the apex thereof to reinforce the tube against collapse, and a cross piece 120 clamped upon the ends of the tube.

LEONARD A. YOUNG.
